UNITED STATES PATENT OFFICE.

JOHN G. SNYDER, OF NEW YORK, N. Y.

METALLIC TIE AND FASTENER.

Application filed December 12, 1924. Serial No. 755,505.

This invention relates to metallic ties and fasteners and has for an object to provide an improved construction wherein means are provided for holding rails on the tie body and also for causing the tie body to remain firmly anchored in a given position.

Another object of the invention is to provide a substantially inverted trough-shaped tie body with an internal stiffening bead extending for the full length and over the turned down ends.

A still further object of the invention is to provide an improved metallic tie wherein the structure is such that a substantially vertical insulating member is positioned intermediate the ends.

An additional object is to provide an improved metallic tie wherein the same is made in a plurality of sections with the abutting sections flattened and turned down to present anchoring means and substantially parallel surfaces for receiving insulating members.

In the accompanying drawing—

Figure 1 is a plan view of a metallic tie and fastener, disclosing an embodiment of the invention.

Figure 2 is a side view of the tie shown in Figure 1, a fastener plate being mounted on each end thereof.

Figure 3 is a transverse sectional view through Figure 1 on line 3—3, the same being on an enlarged scale.

Figure 4 is a top plan view of a modified structure to that shown in Figure 1, the same illustrating an insulated joint.

Figure 5 is a side view of the tie shown in Figure 1, certain parts being shown in section.

Figure 6 is an inverted view of the insulated joint shown in Figure 4.

Figure 7 is a fragmentary sectional view similar to the joint shown in Figure 5 but disclosing a modified construction.

Referring to the accompanying drawing by numerals, 1 indicates the tie body which is substantially U-shaped in cross section as shown in Figure 3 and provided with a depressed portion or groove 2 extending for the full length and over the bent down ends 3 and 4 whereby an interior bead 5 is presented for the entire length of the tie body including the depending ends. This produces a very strong and rigid structure as the bead 5 acts as a reinforcing member without the addition of

metal. The groove 2 also co-acts with fastener plates 6 arranged at each end for presenting overhanging shoulders.

As indicated in Figure 1, rails are adapted to rest on the fastener plates 6 and then suitable clips 7 and 8 applied for holding the same in position. Each of the fastener plates is provided with one or more notches 9 adapted to be engaged by the turned down end of one of the clips while a bolt 10 is positioned with its head in groove 2 and loosely engaging the side walls thereof while the upper part presses against the overhanging portion or shoulders 11 and 12 whereby a proper clamping action is secured.

In forming the ends 3 and 4, the body 1 is bent down as indicated particularly in Figures 1, 2 and 3, whereby a wide transverse flat section 13 is provided. The bead 5 is adapted to extend downwardly to the bottom edge of the section 13. It will be noted that the section 13 is appreciably wider than the body of the tie and functions as an anchor for preventing longitudinal movement of the tie body. Also, when the tie is in use, the roadbed is adapted to be tamped up into the interior of the body 1.

Where a block signal system is to be used, it is necessary to provide an insulation at some point between the rails and it has been found convenient to provide this insulation at the center of the tie as illustrated particularly in Figures 4 to 6 inclusive. From these figures it will be noted that there are presented sections 1' and 1''. Each of these sections is provided with a turned down end 14 which may be formed by pressing in a stamping machine or in any desired manner but formed in such a manner as to present a substantially flat wall 15. A flat strip of insulation 16 is arranged between the respective walls 15 of the sections 1' and 1'' and the respective turned down ends 14 are rigidly secured together by any desired means, as for instance, by the rivets 17 shown particularly in Figure 5 or by bolts 17' shown in Figure 5. In turning down the ends 14, the same are made similar to the ends 3 and 4 except that they are provided with the flat surfaces 15. From Figures 4 and 6 it will also be noted that these ends will flare outwardly and also extend downwardly below the body of the tie for an

appreciable distance, section 18 below the tie being substantially flat and extending beyond the respective sides of the tie body. This structure not only provides for ample space to accommodate rivets, bolts and the like but also provides very desirable anchoring means at the center of the tie so that the turned down ends 3 and 4 could be eliminated if desired. In forming the 10 ends 14, the bead 5 is preferably flattened during the formation of the ends, though if desired, the bead could be left in place and the parts connected together by rivets 17 or bolts 17'. It will, of course, be observed that in forming the ends 14, the sides 15 of the tie body will naturally be flared at points 19 and 20 which will act in a certain sense as braces.

Figure 7 discloses a slightly modified 20 construction to that illustrated in Figures 5 and 6 in that it discloses bolts 17' instead of rivets 17 as shown in Figure 5. Aside from this detail, the construction is the same as shown in Figure 5.

25 What I claim is:

1. A metallic tie including in its construction a body substantially U-shaped in

cross section formed with turned down ends, and an insulating joint arranged between said ends, said joint having turned down 30 portions, insulating means between said turned down portions, and clamping members for clamping said turned down portions together.

2. A metallic tie, including a body formed substantially U-shaped in cross section, said body being provided with flaring turned down ends, and a flaring turned down center section, said body being provided also with a pressed down central portion extending from near the center to the ends whereby interior stiffening beads are provided while the turned down portions at the ends and center present anchoring structures. 40

3. A metallic tie, including a pair of tie sections having abutting turned down ends, said ends being substantially parallel, a vertically positioned insulating plate arranged between said ends, clamping members extending through said ends and insulating plate for securing the ends together, and insulating means positioned between the clamping members and said ends. 45
